UNITED STATES PATENT OFFICE.

CHESTER W. CANINE, OF CINCINNATI, OHIO. ASSIGNOR TO THE NATIONAL MARKING MACHINE COMPANY, OF CINCINNATI, OHIO, A CORPORATION OF OHIO.

MARKING-MACHINE.

1,063,180.

Specification of Letters Patent. Patented June 3, 1913.

Application filed June 21, 1909. Serial No. 503,404.

To all whom it may concern:

Be it known that I, CHESTER W. CANINE, a citizen of the United States, residing at Cincinnati, in the county of Hamilton and State of Ohio, have invented certain new and useful Improvements in Marking-Machines, of which the following is a specification.

My invention relates to a numbering or marking machine, primarily adapted for printing upon clothing, for use in laundries.

One of the objects of my invention is to provide a marking device wherein the marking and setting mechanism is carried by a swinging frame, whereby the type is brought upon the goods in its printing action.

Another object of my invention relates to means whereby a swinging self-contained marking and type-setting head of a numbering machine can be actuated by power driving mechanism.

Another object of my invention relates to a marking machine employing a swinging-head in which an ink reservoir is carried by said head and actuated by the movement of said head to actuate said reservoir to bring its ink distributing surface in direct alinement with the face of the type.

Another object of my invention relates to improved means for controlling the supply of ink to the ink distributing surface.

Another object of my invention is to provide one or more type disks with independent means for actuating each disk, and means for limiting the movement of actuating mechanism, whereby the desired character of each type disk can be brought to its printing position.

Another object of my invention is to provide a series of keys denoting the characters upon the type disk of a numbering machine wherein each key will control the movement of the type disk actuating mechanism enabling each disk of a series to present the same character in printing position.

Various features of my invention are more fully set forth in the description of the accompanying drawings, forming a part of this specification, in which:

Figure 1 is a side elevation of the machine mounted upon a pedestal illustrating a motor power drive. Fig. 2 is a section on line $x-x$, Fig. 3. Fig. 3 is a section on

line $a-a$, Fig. 2. Fig. 4 is a front elevation of the same. Fig. 5 is a rear elevation of the drive and controlling mechanism partly shown in section. Fig. 6 is a detailed view of the drive controlling mechanism. Fig. 7 is a section on line $b-b$, Fig. 6. Fig. 8 is a detailed section enlarged on line $y-y$, Fig. 1. Fig. 9 is an enlarged detail elevation, partly in section, of the lever mechanism on one side of the swinging frame. Fig. 10 is a sectional elevation of the escapement returning mechanism. Fig. 11 is a detailed elevation of the locking mechanism for locking the type disks in their set position. Fig. 12 is a detail side elevation of the lever mechanism controlling and actuating the inking reservoir. Fig. 13 is a detailed elevation of parts of the lever mechanism illustrated in Fig. 12. Fig. 14 is a central vertical section through the escapement mechanism. Fig. 15 is a section on line $c-c$, Fig. 14. Fig. 16 is a section on line $d-d$, Fig. 14. Fig. 17 is a section on line $v-v$, Fig. 15. Fig. 18 is a detailed section of the pivot end of the type disk actuating segment on line $v-v$, Fig. 17. Fig. 19 is an enlarged top plan view of the ink-reservoir. Fig. 20 is a sectional view of the same taken at the ink-distributing portion thereof. Fig. 21 is a detail view similar to Fig. 12, with the parts in printing position.

1, represents a pedestal upon which is supported the main frame 2.

3 represents upwardly projecting brackets formed integral with the main frame 2.

4, 4^a , represent side frames pivotally supported upon the brackets 3, said frames carrying the self-contained marking, type-setting and inking mechanism.

5 represents a series of type disks formed with gear teeth with the indicating characters upon the periphery of the teeth. These disks are loosely journaled upon a spindle 6 mounted in the swinging side frames 4, and 4^a (see Figs. 1 and 4). The type disks of a series are all duplicates of each other and the characters representing numerals from 0 to 9 and the letters of the alphabet. This enables the printing of any number or words, limited only by the number of disks employed.

In the machine illustrated by the drawings fifteen type disks are employed. For each character represented by the type

disks a setting finger is employed and but one series of setting fingers is employed for operating all of the type disks of their series and each disk operated by a single shifting lever. I will, therefore, first describe the mechanism employed in operating a single disk.

7 represents an arched bar formed integral with each side frame 4, 4^a, upon which 10 are pivotally supported the stop levers 8, (see Figs. 1, 2 and 3), projecting inward from each of the side frames 4, 4^a, alternately side by side moving within the notches 9 formed in the guide segment plates 15 10 secured in position upon the side frames by the tie-rods 11. A series of these plates are employed preferably to maintain the alignment of the stop levers their entire length and their spaced position between 20 each other; these being essential to properly register the characters of the type disks in their printing position and printing alignment, also serving to rigidly maintain the stop lever in position against lateral movement when the disk actuating quadrants are brought against the same in setting the disks.

12 represents springs for returning the stop lever to normal position automatically.

13 represents keys the stems of which are 30 loosely connected to the stop levers 8, and project through the face plate 14 secured to the side frames 4, 4^a.

15 represents a sector actuating lever pivoted on the sleeve axle 16, and provided with 35 the rack teeth 15^a, engaging the pinion 17 loosely journaled upon the rod 18, and fixed to a gear 19, the teeth of gear 19 meshing with one of the type disks 5. Thus as the sector lever 15 is swung upward it will 40 move the type disk to the amount of movement governing the setting of a character to its printing position.

20 represents an arm projecting from the sector lever 15, adapted to engage a depressed stop lever 8, to limit the movement of the lever 15, setting the type disk to present the character to its printing position denoted by the depressed key. The keys are so arranged relatively to the movement of 50 sector lever 15, so as to present each character upon the depression of its denoting key. A sector lever 15 and gearing is provided with each type disk of the series with one set of characters denoting keys employed for 55 operating all the type disks of the series which in the construction illustrated requires the operation of the sector levers serially, one at a time. This is accomplished by the following instrumentalities:—21 repre-

60 sents a type-setting manipulating lever pivoted at one end upon the sleeve axle, its opposite end projecting through the face plate 14, forming a hand hold. 22 represents a bell crank lever pivoted to the side 65 frame 4, one arm of which engages an elongated slot 23 formed in the lever 21, (see Fig. 1). The other arm of the lever 22 is provided with a gear segment 24, the teeth of which are in mesh with the teeth of the quadrant 25, fixed to the sleeve 16. 26 represents a slidable key rod slidably mounted within the sleeve axle 16, provided with a key 27 projecting through a slot 28, formed in the sleeve 16. Thus when the sleeve 16 is actuated it will simultaneously actuate the key 27. 29 represents a notch formed in said sector lever 15, (see Figs. 2 and 18), into which notch the key 27 projects, and adapted to engage the shoulder 30 to actuate the sector lever in one direction of movement of the key 27. The notch being large enough to provide a free return of key to normal position without disturbing the shifted position of a sector lever 15.

The key rod 28 is shifted from one sector engaging position to another, as follows:—31 represents a carriage slidably mounted upon the rod 32, fixed to the side frames by means of the arms 33, the lower portion of the carriage traveling upon the cross-plate 34. The carriage 31 is provided with a ratchet plate 35, preferably secured within a groove formed in the base of the carriage. 36 represents an escapement pawl pivotally mounted in a groove formed in the cross-plate 34 adapted to engage with the teeth of the ratchet plate 35. This pawl is operated positively in one direction and automatically in the reverse direction. 32^a represents a spring guide rod secured in the side frames 4, 4^a, and projected through the arms 33, of the carriage, (see Figs. 14, 15, 16, 17 and 18). 37 represents a spring, one end of which bears against one of the arms 33 of the carriage passing through an orifice 38, formed in the opposite arms with the opposite end of the spring bearing against the side frame 4. This spring automatically moves the carriage in one direction and in intermittent step movements by actuation of the escapement pawl. 39 represents an arm projecting from the carriage provided with a pin 40 secured to its free end, the pin 40 projecting downward and engaging into a circumferential groove 41 of the key 42 rod 26. This construction forms a connection between the carriage and key pin, whereby the carriage laterally shifts the key rod 26, without interfering with the rotative movement of the key rod during the rocking of a sector lever in setting the type disks.

The escapement pawl for releasing the carriage in step movements is actuated and controlled, as follows:—The quadrant 25 is provided with a sector projection 42, having a cam surface 43, (see Figs. 14 and 16), adapted to engage a rod 44, loosely supported in the cross-plate 34, the opposite end of the rod 44, engaging the escapement pawl 130

36. 45 represents a spring seated within the cross-plate 34 and bearing against the escapement pawl 36, for automatically returning the same to normal position upon release of the cam engagement with the rod 44.

As illustrated, the carriage is released two step movements upon each setting movement of the type setting lever 21, this being preferable for the reason that the key 27 when 10 the setting lever 21 is in its normal position does not occupy a complete actuating position with a given sector lever 15, but only mid-way therewith. As soon as the actuating lever 21 is moved downward, the cam 15 surface 43 engages the rod 44, releasing one end of the escapement pawl from the ratchet plate and bringing the opposite end of the escapement pawl into engagement with the ratchet plate 35, this permits the movement 20 of carriage the distance of one tooth of ratchet plate, which movement of carriage brings the key 27 into proper sector engaging alignment. The return of actuating lever 21 to normal position, releases the engagement of rod 44 with the escapement pawl, which permits the escapement pawl to be automatically rocked to its normal position, shown in Fig. 14, permitting a second step movement of the carriage.

30 It is desirable after a type disk has been set to present a given character to its printing position to lock the disk against displacement. This is accomplished by the following instrumentalities, (see Figs. 2, 9 and 35 11) :—46 represents a rock shaft journaled in the side frames 4, 4^a, carrying a series of pawls 47, according to the number of type disks employed engaging the pinion 17, of the intermediate transmission gearing between 40 sector lever and type disk. 48 represents a spring for maintaining the pawl 47 under tension against the pinion 17 and engaging between the teeth thereof, as shown in Figs. 2 and 11. This engagement between 45 the pawl 47 and pinion 17 maintains a free rotation of the pinion in one direction and automatically locks the same against reverse movement or rotation. This lock is sufficient to maintain the type disks in their set position. All the pawls 47 of the series are simultaneously disengaged to permit a simultaneous return of type disks and their controlling mechanism to normal position which is accomplished by the following 50 mechanism:—49 represents a lever for actuating the returning mechanism pivotally mounted upon the axle sleeve 16, (see Figs. 9 and 17). All the levers and parts mounted upon the axle sleeve 16, are maintained 55 in position thereon by the bushing sleeves 50, 51, sleeve 50 being slotted, through which the pin 40 projects. 52 represents a lever pivoted to the side frame 4^a, by means of the stud 53, and having a sliding pivotal 60 connection with the lever 49. 54 represents

a lever fixed to the stud 53, and 55 represents a link pivotally connected to the lever 54 at one end and its opposite end to one arm of the bell crank lever 56. 56 represents a bell crank lever pivoted to the side frame 4^a with the arm 57, engaging the lever 58, fixed to the rock shaft 46. (see Fig. 9). The rock shaft 46 is provided with an elongated key or keys projecting into the notch 60, (see Fig. 11) of the pawls 47, the key 59 engaging against the shoulder 61. The notch 60 in each pawl is elongated to permit a free retarding movement of the pawl during the forward rotation of the pinion 17, in setting the type disks. Thus to release the pawls of a series, the lever 49 is swung downward actuating levers 52, 54, link 55, bell crank lever 56, actuating the rock shaft 46, bringing the key or keys 59 into engagement with the shoulders 61, of the pawls 47 of the series, disengaging the same simultaneously from their respective pinions, permitting a reverse rotation of the pinions 17 and type disk setting mechanism. The carriage 31 is returned, as follows:—(See Figs. 9 and 10). 62 represents a lever pivotally connected at one end upon a sleeve 63, upon the stud 53, the opposite end of said lever having a sliding connection with the carriage 31 by yoking the end over the screw 63. 64 represents a roller journaled upon the lever 62 and traveling over the cam surface 65 formed upon the lever 52. Thus as the lever 52 is actuated, the cam surface 65 will cause the lever 62, to be swung to return the carriage 100 31 to normal position against the tension of the spring 37.

The type disks and their actuating mechanism are returned to normal position, as follows:—As illustrated in Fig. 2, the type-setting mechanism is in normal position, a setting action causing the sectors to move toward a vertical position and as they are usually set at different positions relative to each other according to the various characters set to printing position, a T-lever 66 is provided pivotally mounted so that in its arc of movement it will engage all of the sector levers 15 of the series, moving the same to normal position simultaneously. The T-lever 66 actuated by the lever 49, by means of the link 67, pivotally connected to the lever 49 at one end and its opposite end to the arm 68, fixed to the rock-shaft or rod 32, journaled in the side frames 4, 4^a, the 110 T-lever in turn is connected to said rock-shaft.

Great difficulty has heretofore been experienced in marking machines to properly ink the type and properly present the inking-pad relatively to the face of the type. With my invention, the inking-pad is presented to the type face in a parallel line therewith and pressed uniformly over the entire surface of the characters as contra- 125 130

distinguished from a rubbing action across the faces of the characters. In this respect, I believe, that I am the first to provide a self-contained type-carrying, setting, inking and marking device, presenting an inking surface parallel with the face of the type to present a pressing action of inking surface against the type face and withdraw therefrom in the same plane. This enables 5 a uniform distribution of ink to each set character of the series and avoids distributing ink to the next adjacent characters. The construction and actuation of ink reservoir, as illustrated, also prevents a promiscuous 10 throwing of ink in a rapid printing. As the machine illustrated is designed to be driven by power, the inking problem is an important one. 70 represents an ink reservoir, the upper surface of which is provided with a 15 pad groove, into which the pad 71 is inserted, (see Figs. 19 and 20). This groove is provided with a series of orifices 72. 73 represents a valve plate provided with a series of orifices 74, said valve plate being adapted 20 to be moved over the orifices in the reservoir by means of the screw 75, for controlling the supply of ink to the pad. By this construction, a very delicate adjustment 25 can be obtained to the valve and the supply 30 of ink regulated with nicety.

The ink reservoir is actuated to and from the surface of the type disk, as follows:— 35 76 represents upwardly projecting arms, see Figs. 12 and 13, fixed to the studs 77, forming the fulcrum for the side frames 4, 4^a. A duplicate construction of lever mechanism 40 being carried out upon each side of the ink reservoir. 78 represents a lever pivotally mounted upon the arm 76, to the forward end of which is pivotally connected the link 79, the opposite end of said link being pivotally connected to the rear portion of the 45 ink reservoir 70. 80 represents a link lever pivotally connected to the lever 78, and to the inking reservoir 70 at one end and the main side frame 4. 81 represents 50 a pin fixed to the arm 76, against which the lever 78 engages to impart the final inking movement to the reservoir 70. 82 represents a table or printing platen, provided with a cushion surface 83, upon which the goods to be marked is placed and against which the type strikes in its printing action. 84 represents a guard pivotally mounted, the upper surface of the 55 guard being concave of a radius to not contact with the type disks and provided with a slot 85, through which the set characters pass in printing. 86 represents guards mounted upon each side of the table serving 60 as guides in properly presenting the work to be marked upon the table. With a guard 84, constructed as illustrated, it prevents the operator from bringing any portion of the 65 goods other than upon which it is desired

to print in contact with the type disk, which is important in this class of machines, in which an indelible ink is used, as it would be very detrimental to the laundry, inasmuch as it would spot the goods of its customers. 70

As illustrated, the machine is designed to be operated by power, which is essential to produce a rapid printing, especially for laundry purposes, where quite a number of pieces are marked with the same character 75 for identification. 90 represents an electric motor, (see Fig. 1), supported by the pedestal 1. 92 represents a belt connected with a motor pulley, and pulley 93 loosely mounted upon the shaft 94. 96 represents a disk 80 fixed upon shaft 94, and 95 a leather friction disk between the disk 96 and face of the pulley wheel 93. Thus, as the shaft 94 is moved to the right it will bring the friction disk into contact with the pulley transmitting power to shaft 94. 97 represents a nurl for adjusting the disk 96 relatively to the pulley 93 for increasing or decreasing the frictional contact. 98 represents a pinion fixed on shaft 94, in mesh with a gear 90 100, fixed upon the shaft 101. 102 represents a pinion fixed on shaft 101 in mesh with a gear 103, fixed upon a stud shaft. The gear 103 is provided upon one side with a cam surface 105, against which the clutch 95 shifting lever bears to maintain the clutch in driving relation with the pulley 93, for one revolution of the gear 103, to make one impression of the type disks. The lever 106 engaging against the collar 107, fixed to the 100 shaft 94. 108 represents a rod connected to the lever 106 at one end with its opposite end connected to the treadle lever 109. 110 represents a spring for maintaining the lever 106 in contact with the cam of gear 105 103, and automatically returns the same to normal or released position. Thus, to effect but one printing action of the frame, the treadle lever 109 is depressed, which action moves the shaft 94, so as to bring the friction clutch into action and held in such position until the cam surface of the gear 103, engages the lever 106, automatically releasing the engagement at the end of the cam surface. 115

It is desirable to lock the transmitting mechanism against rotation upon disengagement of clutch to prevent lost movement which is accomplished automatically, as follows:—111 represents a flange projecting 120 from gear 100. 112 represents a strap pivotally connected at one end to the base 2 and engaging upon the flange 111, with the opposite end connected to the lever 106. Thus it will be seen that a brake will be applied 125 to the transmission mechanism as soon as lever 106 is released, and vice versa. 113 represents a pitman pivotally connected to one face of the gear, and to the side frames 4, 4^a. 130

Having described my invention, I claim:

1. In a marking machine, a base, a stationary printing platen thereon, a swinging frame mounted on said base, a series of type disks journaled on said frame, their peripheries arranged in the form of gears, a sector for each type disk mounted on said swinging frame, transmission elements between each sector and each type disk, means for serially actuating the sectors operative by a single lever for presenting a character upon the type disk to its printing position, means for locking each type disk in its adjusted position, and means for rocking said frame to and from said platen.
2. A marking machine comprising a swinging frame, a series of type disks journaled thereon, a sector lever for each type disk in operative connection therewith, means for serially swinging said levers, character indicating key levers movable in the path of the sector swing for limiting the movement thereof, and common to all the sectors of the series, to present a given character upon the type disk to its printing position, a printing platen, and means for moving said swinging frame to and from said platen.
3. A marking machine comprising a swinging frame, a series of type disks mounted thereon, means for actuating each disk independently to present a given character upon the type disk to its printing position, a series of type disk character designating keys of a number equal to the number of characters on a single disk, means whereby said keys will control the actuation of all the type disks of the series for presenting a given character of each type disk to its printing position, a stationary printing platen, means for swinging said frame to and from said platen, and inking means upon said frame movable therewith end to and from the type disks relatively with the rocking action of said frame.
4. In a marking machine, a swinging frame, a series of type disks supported thereon, means for independently serially revolving each disk to set a given character on each disk to its printing position, means for independently locking each disk of the series in its set position, means for simultaneously releasing all of said locks of the series, means for simultaneously returning all of the disks to normal position, a single lever for operating said lock releasing mechanism and disk returning mechanism.
5. In a marking machine, a swinging frame, a series of type disks supported thereon, means for independently serially revolving each disk to set a given character on each disk to its printing position, means for independently locking each disk of the series in its set position, means for simultaneously returning all of the disks to normal position,
6. In a marking machine, a swinging frame, a series of type disks supported thereon, independent means for revolving each disk to set a given character on each disk to its printing position, means for serially operating said disk revolving means, comprising a carriage automatically movable in one direction, clutching devices carried by said carriage, adapted to be moved into clutching position with said disk revolving means, combined means for tripping said carriage and actuating said disk revolving means, a stationary printing platen, and means for rocking said frame to and from said platen.
7. In a marking machine, a swinging frame, a series of type disks supported thereon, means for independently revolving each disk to set a given character on each disk to its printing position, means actuated by a single lever for serially operating said disk revolving means, means for simultaneously returning all the actuated parts to normal position, a printing platen, and means for rocking said frame to and from said platen.
8. In a marking machine, a swinging frame, a series of type disks supported thereon, means in connection with each type disk for revolving the same, a carriage movable automatically in one direction of its travel, means carried by said carriage adapted to engage with any one of said type disk revolving means of the series, means for tripping the carriage in step movements to align the carriage relatively to a given disk and actuate the same, means for limiting the revolutions of the type disk, a printing platen, and means for rocking said frame to and from said platen.
9. In a marking machine, a swinging frame, a series of type disks supported thereon, independent means for revolving each disk comprising a member pivotally supported and in actuating connection with its respective type disk, a sliding key adapted to serially engage said type revolving members, a carriage for shifting said key, means for intermittently moving said carriage, means for actuating said key after engagement with a disk revolving member, means for simultaneously returning said carriage and parts to normal position, a printing platen, and means for rocking said frame to and from said platen.
10. In a marking machine, a frame, an oscillating printing-head, a key-board thereon, type disks and setting mechanism mounted within the frame and adapted to move into printing position, a character on each disk corresponding to the character of the

- key depressed, means for returning the disks and setting mechanism to normal position, in combination a work supporting table, a swinging guard having an opening through which the set characters pass in printing and guard against contact of the goods from the face of the remainder of characters of the disk, guides mounted upon each side of the table for properly presenting the work upon the table.
11. In a marking machine, a frame, a platen thereon, a printing-head reciprocally mounted on the frame, printing and setting mechanism organized wholly within the head, and comprising a series of type disks, a key-board having characters corresponding to the characters of each disk, a setting mechanism for each disk, a setting lever, and a carriage adapted to be moved serially into operative position relative to the setting mechanism of each disk to throw into printing position serially on each disk the character of the key depressed, means for returning the disks, setting mechanism and carriage to initial position, and an inker on the head automatically actuated by the movement of the head relative to the fixed frame to ink the characters of the disk alined for printing.
12. In a marking machine, a swinging frame, a series of type disks journaled thereon, a sector lever for each disk in operative connection therewith, character indicating key levers, movable in the path of said sector swing, for limiting the movement thereof, and common to all the sectors of the series, and means for serially operating said sectors comprising a carriage automatically movable in one direction, means movable therewith adapted to engage with each sector, and means for rocking the same to actuate a given engaged sector, and thereby revolve its disk to adjust a character thereon to printing position, a printing platen, and means for rocking the frame to and from said platen.
13. In a marking machine, a swinging frame, a series of type disks journaled thereon, a rocking type disk actuating lever, intermediate connections between said type disks and lever, means in connection with, and actuated in step movements by said lever, for serially engaging said intermediate connections to operate the same, means for limiting the movement of said rocking lever to rotate the type disks to present given characters thereon to printing position, and a second rocking lever for restoring all parts to normal position.
14. In a marking machine, a swinging frame, a series of type disks journaled thereon, a sector lever for each, and in connection therewith, means for serially operating each sector lever, comprising a swinging lever, a carriage movable automatically in one direction, tripping means for releasing said carriage in step movements upon each operation of said lever, and means movable with the carriage and lever serially engaging the sector levers, for operatively connecting the same with said swinging lever for individual adjustment of each type disk, to present a given character thereon to printing position.
15. In a marking machine, a base, a printing platen thereon, a swinging frame mounted on said base, a series of type disks journaled on said frame, a rock lever journaled on said frame, intermediate transmission mechanism between said rocking lever and each of the type disks and independent of each other, means automatically movable in one direction, escapement mechanism therefore, to control its action in step movements, and means for controlling said escapement mechanism on each movement of said rocking lever, thereby serially engaging said intermediate disk transmission mechanism with the rocking lever, to rotate the disk, and means key-controlled for governing the limits of type disk adjustment to present a given character thereon to its printing position, means for locking each type disk in its adjusted position, and a second rocking lever for returning the various elements to normal position.
16. In a marking machine, a swinging frame, a series of type disks supported thereon, means for independently revolving each disk to set a given character thereon to its printing position, means actuated by a single lever for serially operating said disk revolving means, a series of spring-controlled pawls for locking each type disk in its adjusted position, a second lever for returning the parts to normal position, and means interposed between said locking pawls and second lever for simultaneously releasing said disks, a printing platen, and means for swinging said frame to and from said platen.
17. In a marking machine, a swinging frame, a series of type disks supported thereon, means for independently revolving each disk to set a given character thereon to its printing position, means actuated by a single lever for serially operating said disk revolving means, means for independently locking each disk of the series in its set position, means for simultaneously returning all of the disks to normal position, a second lever for operating said lock releasing mechanism, and disk returning mechanism, provided with means for effecting a lock release in advance of the disk return.
18. In a marking machine, a base, a swinging frame, a series of type disks supported thereon, means for independently revolving each disk to set a given character thereon to its printing position, means actuated by a single lever for serially operating said disk revolving means, means for simultaneously

- returning all of the actuated parts to normal position, an ink reservoir and inking pad, lever mechanism pivotally connected to said ink reservoir, base and swinging frame, and 5 controlling means therefor, to present the inking pad parallel with and against the face of the type during a portion of the frame movement in a printing action, a printing platen, and means for rocking the 10 swinging frame to and from said platen.
19. A marking machine comprising a swinging frame, a series of type disks mounted thereon, means for actuating each disk independently to present a given character 15 upon the type disk to its printing position, a series of type disk character designating keys of a number equal to the number of characters on a single disk, and means whereby said keys will control the actuation 20 of all the type disks of the series for presenting a given character of each type disk to its printing position.
20. In a marking machine, a swinging frame, a series of type wheels journaled 25 thereon, a setting member for each type wheel, character indicating key lever movable in the path of the setting members for limiting the movement thereof and common to all the setting members of the series.
21. In a marking machine, a swinging frame, a series of type wheels journaled thereon, a setting member for each type wheel, character indicating key lever mov- 30 able in the path of the setting members for limiting the movement thereof and common to all the setting members of the series, a printing platen and means for rocking said frame to and from the printing platen.
22. In a marking machine, a swinging frame, a series of type wheels journaled 35 thereon, a setting member for each type wheel, character indicating key lever movable in the path of the setting members for limiting the movement thereof and common to all the setting members of the series, ink- 40 ing mechanism coöperating with the movement of the frame to ink the type characters set in printing position, a printing platen and means for rocking the frame to and from the printing platen.
23. In a printing machine, the combination of a swinging head, a series of type wheels thereon, adapted to be selectively actuated in their serial order to present in printing position an alinement of selected 45 characters to be printed, and key mechanism common to all type wheels controlling the selection comprising the characters of the type wheels.
- In testimony whereof, I have hereunto 50 set my hand.
- CHESTER W. CANINE.
- Witnesses:
- OLIVER B. KAISER,
EMMA SPENER.
